UNITED STATES PATENT OFFICE

139,135

DESIGN FOR A BOTTLE

Vaughn E. Bowers, Saratoga, Ind.

Application April 5, 1944, Serial No. 113,150

Term of patent 14 years

(Cl. D58—6)

To all whom it may concern:

Be it known that I, Vaughn E. Bowers, a citizen of the United States, residing at Saratoga, in the county of Randolph and State of Indiana, have invented a new, original, and ornamental Design for Bottles, of which the following is a specification, reference being had to the accompanying drawing, forming a part thereof.

I claim:

The ornamental design for a bottle, substantially as shown.

VAUGHN E. BOWERS.
